CLAIM

The ornamental design for a nasal dilator, as shown and described.

DESCRIPTION

FIG. 1 is a top plan view of a first embodiment of a nasal dilator.

FIG. 2 is a side view thereof where the nasal dilator is in a state of use.

FIG. 3 is a perspective view thereof.

FIG. 4 is a top plan view of a second embodiment of a nasal dilator.

FIG. 5 is a side view thereof where the nasal dilator is in a state of use; and,

FIG. 6 is a perspective view thereof.

In the drawings, the equal length broken lines showing human facial features are directed to environment and form no part of the claimed design. The equal length broken lines showing portions of the nasal dilator form no part of the claimed design. The long dash-short dash-long dash broken lines in FIGS. 1-3 define the bounds of the claimed design and form no part thereof.
